GASOLINE PUMP

Benjamin G. Bowden, Short Hills, N. J., assignor to John Wood Company, New York, N. Y., a corporation of Delaware

Application November 25, 1957, Serial No. 48,653

Term of patent 14 years

(Cl. D52—2)

FIG. 1

FIG. 2

FIG. 3

Fig. 1 is a front elevation of a gasoline pump embodying my new design.

Fig. 2 is a side elevation thereof.

Fig. 3 is a top plan view thereof.

The undisclosed side and rear of the gasoline pump are substantially the same in appearance as the side and front shown in the drawing.

I claim:

The ornamental design for a gasoline pump, as shown and described.
